UNITED STATES PATENT OFFICE.

JAMES R. ANDRUS, OF WOODLAND, WASHINGTON.

UNDERCUTTER.

1,221,128.

Specification of Letters Patent.

Patented Apr. 3, 1917.

Application filed September 14, 1914. Serial No. 861,578.

To all whom it may concern:

Be it known that I, JAMES R. ANDRUS, a citizen of the United States, residing in the town of Woodland, Cowlitz county, and 5 State of Washington, have invented certain new and useful Improvements in Undercutters, of which the following is a specification.

My invention relates to undercutters for 10 use in sawing logs, and more particularly to a device adapted to be attached to a log for the purpose of supporting a saw while sawing the log from the under side. Among the salient objects of my invention 15 are,—to provide a small portable device which can be driven into a log and anchored in such a way that it will be impossible for it to get loose or work out of the log during the operation of the saw; to provide a device 20 of the character referred to having a roller bearing member upon which the saw runs which can be quickly and conveniently adjusted to different positions without removing the saw therefrom and which automatically locks against downward movement under the weight of the saw thereupon; and, 25 in general, to provide a device of the character referred to which is simple, efficient and economical.

30 In order that others may fully understand my invention, I have shown in the accompanying sheet of drawings one practical embodiment thereof which I will now describe. In the drawings,—

35 Figure 1 is a side view of one embodiment of the invention, showing the log and the saw in light broken lines; and

Fig. 2 is a top plan view of the device, showing the saw in light broken lines.

40 My invention as here illustrated comprises a body 1, having a flat, sharp, upwardly curved prong, or toe, 2, adapted to be driven into the log, shown in dotted lines, and a heel piece 3, adapted to engage the log at a 45 point below the prong 2, substantially in the manner indicated.

Pivots attached to the body 1 is a crank member 4, provided at its attached end, at 50 opposite sides of the body, with ratchet wheels, as 5 and 6, secured to said crank member and turning therewith. Mounted upon the body 1 is a pawl 7, normally held in engagement with the ratchet wheel 5 by means of a spring 8. The portion of the 55 crank 4 which passes through the ratchet wheels 5 and 6 and the body 1 is made

square, as indicated by dotted lines at 4^a, while the extreme upper end portion thereof is reduced in size and threaded to receive a thumb nut 9, thus making it possible to regulate the frictional contact between the ratchet wheels and the body 1.

At the lower end of said crank 4 is a bearing member 10, having a wooden middle portion 10^a, to make it lighter, and having a 60 ball-bearing connection at 10^b upon the crank member 4. The rim of the bearing member 10 is preferably of steel and is provided with a series of circumferentially extending grooves, adapted to receive the back 70 edge of a saw, shown in light broken lines and designated S.

The crank 4 and the bearing member 10, it will be noted, are adjustable to various positions by simply moving them by hand in 75 one direction, the pawl 7, however, engages with the ratchet wheel 5 in such a way as to prevent said crank and bearing member from moving back in the opposite direction.

By providing two ratchet wheels, as 5 and 6, at opposite sides of the body 1, it is possible to readily transfer the crank 4 and its bearing member 10 to the opposite side of the body, which may be found necessary, or 80 at least convenient, in some cases.

85 The operation of the device may be briefly described as follows:

The body of the device, of course, is made 90 of steel or other suitable metal, and adapted to be driven into the log in the manner indicated. The prong 2 is made sharp and flat and curved upwardly, substantially as indicated. When driven into the log until the heel 3 engages the log, as indicated, it will be seen that any downward weight upon 95 the body will have a tendency to increase the upward, frictional holding engagement of the curved prong with the log into which it is driven, thus making it impossible to pull the prong out of the log by forcing the body 100 1 downwardly at its outer end. If the prong were straight, or curved in the opposite direction, it would be easily pulled out and would work loose under the weight and operation of the saw. The crank 4 is shown in 105 its downmost position in light broken lines. This is the position it would usually occupy in starting the saw into the underside of a log. As the cut is made and the saw works up into the log, the crank 4 and the bearing 110 10 can be raised, as indicated in the solid line position, by simply lifting it by hand, and

the pawl and ratchet 5 operate automatically to prevent said crank and bearing member from moving down under the weight of the saw as it is operated through the log. As 5 the cut is extended up through the log, the crank member can be raised until it extends upwardly in a vertical position above the body.

I am aware that changes can be made in 10 the embodiment of the invention here shown for purposes of illustration without departing from the spirit thereof, and I do not, therefore limit the invention to the particular form shown, except as I may be limited 15 by the hereto appended claims.

I claim,—

1. An undercutter of the character described comprising a body having an upwardly curved prong adapted to be driven 20 into a log and a heel portion adapted to engage the log at a point below said prong, and a bearing device adjustably mounted on said body for supporting a saw.

2. An undercutter of the character referred to comprising a body having an upwardly curved prong adapted to be driven 25 into a log and a heel adapted to engage the log at a point below said prong, and a crank member adjustably secured to said body and provided with a bearing element adapted to 30 support a saw during its operation.

3. An undercutter of the character shown and described, comprising in combination, 35 an integral body having a flat, upwardly curved prong adapted to be driven into a log, and an off-set heel portion adapted to engage the outside of the log at a point below said prong, whereby any downward

strain on the outer end of said device tends to wedge said prong in said log and increase 40 its friction hold therein, a saw supporting member pivotally supported on said device.

4. An undercutter of the character described comprising a body having an integral, flat, sharp, upwardly curved prong 45 adapted to be driven into a log and an integral heel portion at a space from said prong adapted to engage the log at a point below said prong, and a saw supporting member mounted on the body.

5. A device of the character described comprising a body member split at one end and having one part formed into a flat, upwardly curved prong adapted to be driven 55 into a log, and the other part extended downwardly and adapted to engage the log at a point below, and a saw supporting member mounted on the body.

6. An undercutter comprising an upwardly curved prong adapted to be driven 60 into a log, with a heel portion formed integrally therewith and adapted to engage the outside of the log as a brace, said prong being adapted to pull out easily by upward strain on its outer under end, but to resist 65 pressure on its upper outer end, and an adjustable crank arm with roller supporting member for the saw, substantially as shown and described.

Signed at Portland, Multnomah county, 70 Oregon, this 9th day of September, 1914.

JAMES R. ANDRUS.
